(57) **CLAIM**

The ornamental design for an LED flashlight lantern, as shown and described.

DESCRIPTION

FIG. 1 is a top, front and side perspective view of an LED flashlight lantern showing my new design;

FIG. 2 is a top, rear and side perspective view thereof;

FIG. 3 is a front elevational view thereof;

FIG. 4 is a side elevational view thereof from the left of FIG. 3;

FIG. 5 is a side elevational view thereof from the right of FIG. 3;

FIG. 6 is a rear elevational view thereof;

FIG. 7 is a top plan view thereof; and,

FIG. 8 is a bottom plan view thereof.

The broken line showing of details of the claimed design is included for the purpose of illustrating only and forms no part of the claimed design.
